SAFETY ATTACHMENT FOR WRIST BANDS

Bernard Mestekin, Washington, D. C.

Application June 8, 1935, Serial No. 25,664

3 Claims. (Cl. 63—3)

One object of my invention is in making a safety attachment to be used in connection with bracelets either used as jewelry or when used together with a wrist watch.

5 Another object of my invention is to make a safety attachment for the purpose stated above which will be simple to manufacture, durable and of reasonable cost.

Another object of my invention consists in 10 making the safety attachment in a way that it will not become detached accidentally but only by the operation of the user.

Another object of my invention is in making 15 the device detachable from any bracelet in use and transferable to another bracelet.

Still another object lies in the ease of operating the device with one hand without sacrificing its function as a positive safety device.

For a clearer understanding of the invention 20 reference is made to the annexed drawing in which

Fig. 1 is a perspective view of an embodiment of my invention shown as used with a wrist watch.

25 Fig. 2 shows in perspective one preferred form of my safety device intended to be used with a cord watch bracelet.

Fig. 3 is an end view on an increased scale of the safety device shown in Fig. 2.

30 Fig. 4 is a similar end view to Fig. 3 but showing a modified form of the device intended to be used on a bracelet of substantially rectangular section as is common in ribbon bracelets and bracelets commonly used as jewelry.

35 Referring in more detail to the drawing 10 represents a wrist watch as it is worn on the wrist with the elements 11—12 of a cord bracelet attached to the watch in the conventional manner. Such bracelets are usually provided with a snap fastening means 13—14 the common construction of which includes a latch means 15 cooperating in a detent 16. In the ordinary wear 40 the latch means becomes worn and unsafe opening up easily and causing the loss of both watch and wristlet. To prevent this I provide a safety attachment which consists of two ring elements 17, 18.

These ring elements are slipped upon the bracelet one at each end thereof and held there from 45 accidental detachment by the larger size of the

fastening means 13—14. One of these ring elements as shown at 17 is provided with an eye 19 to which I permanently attach one end of a safety chain 20. The other end of the chain I provide with an oblong link 21 shaped substantially like 5 a keyhole. This link 21 with the larger opening attached to the chain acts as a form of bayonet locking joint cooperating with a complementary locking member 22. The locking member 22 is a short rod terminating in a head 23 the head being 10 larger than the slot in the element 21.

It is evident from an inspection of this form of construction that the straddling chain can not become accidentally detached, and will become detached only when the user will push the 15 link 21 on the rod of the member 22 until the head 23 can clear and pass through the larger opening of the link 21.

Having described the device I claim as my invention:

1. A safety attachment for use in conjunction 20 with the lock of a fastening means of a piece of jewelry comprising in combination two ring members and a chain straddling them, said chain being permanently attached to one of said ring 25 members and means on the other ring member cooperating with an end link on the chain for detachably connecting the chain to said other ring member, each of the said ring members adapted to embrace an end of the fastenings 30 means across the lock thereof.

2. A safety attachment for use in conjunction 35 with the lock fastening of a piece of jewelry, in combination two ring members a chain having one end permanently attached to one of said ring members and a bayonet joint arrangement for detachably connecting the other end of the chain to the other ring member, each of said ring members encircling an end of the fastening means across the lock.

3. In an article of jewelry having separable 40 end portions provided with means for locking the same together, a safety attachment therefor comprising in combination two members shaped to fit around and to be secured to the respective end 45 portions of the article of jewelry, a chain permanently attached at one of its ends to one of said members and means for detachably connecting the other end of said chain to the other member.

BERNARD MESTEKIN. 50
